OF BRONSON, MICHIGAN, A CORPORATION OF MICHIGAN.

REFLECTING ELECTRIC LAMP.

1,313,473.

Specification of Letters Patent.

Patented Aug. 19, 1919.

Application filed November 21, 1917. Serial No. 203,099.

To all whom it may concern:

Be it known that I, HARRY A. DOUGLAS, citizen of the United States, residing at Bronson, in the county of Branch and State of Michigan, have invented a certain new and useful Improvement in Reflecting Electric Lamps, of which the following is a full, clear, concise, and exact description.

My invention relates to reflecting electric lamps and has for its general object the provision of improved means for assembling component parts thereof.

A reflecting lamp made in accordance with my invention includes a reflector containing casing 1, a lamp 2, two tubular elements, one within the other, one receiving the lamp and surrounded by the other that is connected with the casing, an integral portion of one of said tubular elements 20 constituting a circumferentially extending spring formation that bears upon the other tubular element to hold it. The outer tubular element is the one that desirably has the circumferentially extending spring formation and this spring formation is desirably inclusive of two oppositely directed circumferentially extending alined springs. The circumferentially extending springs not only perform the function for which these springs are provided but these springs also constitute continuing parts of the tubular element having them. By extending these springs circumferentially instead of longitudinally the portion of the tubular element in which they are provided need not be as long, for a given degree of spring pressure, as would be necessary if the springs extended longitudinally. Moreover, the outer ends of the springs are, in the preferred embodiment of the invention, separated sufficiently to form a longitudinal slot in the tubular element having the springs, the other tubular element having a lateral formation in abutting and sliding engagement with the aforesaid outer ends of the springs to prevent relative rotation of the tubular elements while permitting their relative longitudinal movement for the purpose of focusing the lamp. The springs also serve to hold the inner tubular element in axial alinement with the outer tubular element and do not tend to warp or slant the inner tubular element.

I will explain my invention more fully 55 by reference to the accompanying drawings

showing the preferred embodiments thereof and in which Figure 1 is a view, partially in longitudinal section and partially in elevation, showing portions of a reflecting lamp made in accordance with the invention; Fig. 2 is a view on line 2—2 of Fig. 1; Fig. 3 is a bottom view, excepting for the reflector which is shown in section, of the structure as it appears in Fig. 1; Fig. 4 is a view on line 4—4 of Fig. 3; Fig. 5 shows, partially in section and partially in elevation, a modification of the structure shown in Fig. 1; Fig. 6 is a view on line 6—6 of Fig. 5; Fig. 7 shows, partially in section and partially in elevation, another 70 modification; Fig. 8 is a view on line 8—8 of Fig. 7; Fig. 9 shows another modification, partially in section and partially in elevation; Fig. 10 is a side view of a part of the structure shown in Fig. 9; and Fig. 11 is a view on line 11—11 of Fig. 9.

Like parts are indicated by similar characters of reference throughout the different figures.

Reference will first be made to the construction shown in Figs. 1 to 4 inclusive.

The reflector containing casing 1 has a reflector provided directly upon its front face in the construction shown in these figures. The base of the lamp 2 is provided with bayonet pins 3 that are received within the bayonet slots 4 provided in the forward end of the inner tubular element or shell 5. The lamp filament 6 is connected with the contacts 7 upon the base of the lamp. A plug 8 is received within the rear end of the shell 5 and is suitably coupled with said shell. This plug carries forwardly spring pressed contacts 9 that are engageable with the contacts 7 upon the base of the lamp that is received in the front end of the shell. The outer tubular element 10 is coupled with the casing 1 and constitutes a holder for the shell 5 whereby said shell and lamp are assembled with the casing 1. The holder or outer tubular element 10 is provided with a circumferentially extending slot 11 at the middle of the holder 10 and a wide longitudinally extending slot 12 at the rear of the holder which communicates with the slot 11 whereby the rear part of the holder has, integrally formed with the balance of the holder, two alined circumferentially extending oppositely directed springs 13. The inner tubular element or shell 5 is formed

with lateral projections 14 that have abutting and sliding engagement with the outer or free ends of the springs 13, those ends which margin the wide slot 12. While 5 undue relative rotary movement between the shell 5 and its inclosing holder 10 is prevented by the engagement of the portions 14 of the shell with the spring portions 13 of the holder, longitudinal movement of the shell 10 within the holder is permitted whereby the lamp may be focally adjusted with respect to the reflector on the front face of the casting 1. The two springs 13 and the common base thereof afford at least three points, 15 distributed around the circle of the shell, where the holder 10 has holding engagement therewith and as the shell is in sliding fit with the holder inclosing it the spring portions 13 of the holder not only serve to 20 maintain the shell and holder in assembly but do not tend to throw the shell out of axial alignment with the holder. The rear holder extensions 13¹ prevent the shell 11 from being rearwardly removed.

25 The construction shown in Figs. 5 and 6 has many points in common with the construction shown in Figs. 1 to 4 inclusive and similar parts are given similar characters of reference.

30 In Fig. 5 the reflector containing casing 1 is spaced apart from the reflector 15 contained therein in which event the shell 5 is provided with some suitable adjusting means that extends through the back of the casing, it being understood that said casing 35 is connected or assembled with the reflector 15 and thereby with the holder 10. I have shown an angular lug 16 in fixed connection with the shell 5 and in threaded engagement with a screw 17 whose head 18 is 40 upon the exterior of the casing. This screw is confined to a single plane of rotation so that as it is turned the shell is moved backwardly or forwardly to effect the focal adjustment of the lamp. Instead of providing 45 the projections 14 to limit the rotation of the shell within the holder, I employ a bulge 19 in the shell 5 that performs this function and which also serves to hold the angular lug 16 in position between the plug 8 and the shell whereby the assembly of the lug and shell is effected.

50 In the construction illustrated in Figs. 7 and 8 there are shown parts similar to parts shown in Figs. 1 to 4 inclusive and these parts are given similar characters of reference. In these Figs. 7 and 8 there are illustrated two circumferentially extending slots 20 in the rear portion of the shell 5 rather than in the inclosing holder 10 and spaced apart longitudinally of the shell. The shell 5 also has a longitudinally extending slot 21 that joins the slots 20 to form two aligned circumferentially extending oppositely directed springs 22. The holder 10

has a longitudinal slot 23 into which the outwardly projecting outer ends of the springs 22 are extended. The longitudinal edges of the slot 23 in the holder 10 have abutting engagement with the outer ends 70 of the springs 22 whereby relative rotary movement of the shell and holder are prevented. The longitudinal edges of the slot 23 in the holder 10 also have sliding engagement with the outer ends of the springs 22 75 whereby the shell 5 may be adjusted longitudinally of the holder 10 to effect focal adjustment of the lamp. The plug 8 has a rearward extension in the form of a threaded rod 24 which is in threaded connection with a rotatable sleeve 25. This sleeve 25 is mounted within the rear end of the holder 10 that extends to the rear of the casting 1 and is coupled therewith as illustrated. The sleeve 25 is confined to a single 80 plane of rotation so that as it is turned the rod 24 and the plug 8 to which the rod is attached are movable backwardly and forwardly to effect focal adjustment of the lamp.

85 In the arrangement shown in Figs. 7 and 8 portions 22, in addition to taking part in forming the lamp receiving shell 5, also form springs that press outwardly upon the surrounding holder 10.

90 The construction shown in Figs. 9, 10 and 11 has a number of characteristics in common with the construction shown in Figs. 1, 2, 3 and 4, the holder 10 in both constructions having circumferentially disposed springs 100 formed therein. The construction shown in Figs. 9, 10 and 11 also has a number of features in common with the construction shown in Figs. 7 and 8 but differs from the construction shown in Figs. 7 and 8 as these latter figures show the circumferentially disposed springs formed in the shell that holds the lamp base at its front and the plug at its rear.

95 The parts of the structure shown in Figs. 110 9, 10 and 11 which are similar to parts shown in the other figures are given similar characters of reference. The shell 5 has a slot 5¹ therein arranged in the zone of the springs 13² that form part of the holder 115 10 and which springs are provided with noses 13³ that enter the slot 5¹. Relative circumferential movement of the holder and shell is prevented by the engagement of the noses 13³ with the longitudinal margins of 120 the slot 5¹. Movement of the shell longitudinally of the holder is permitted by making the slot 5¹ longer than the width of the springs 13². The extent to which the shell 125 may be moved forwardly is limited by the engagement of the rear edge of the slot 5¹ with the noses 13³. The extent to which the shell may be moved rearwardly is limited by the engagement of the forward edge of the slot 5¹ with the noses 13³.

Another difference between the structure of Figs. 9 to 11 inclusive and the structure in Figs. 1 to 4 inclusive resides in the fact that the slot that separates the adjacent ends 5 of the springs 13² does not extend to the rear of the holder since the holder extends too far to the rear for such elongation of the slot.

In all forms of the invention the circumferentially aligned oppositely directed springs serve to engage the tubular element complementary to the tubular element having these springs to center and maintain in alignment the tubular elements without requiring increase in the lengths of the tubular elements having the springs in order that the springs may perform their functions.

While I have herein shown and particularly described the preferred embodiment of my invention, I do not wish to be limited to the precise details of construction shown as changes may readily be made without departing from the spirit of my invention, but having thus described my invention I claim as new and desire to secure by Letters Patent the following:—

1. A reflecting electric lamp including a reflector containing casing; a lamp; and two tubular elements, one within the other, one receiving the lamp and surrounded by the other that is connected with the casing, one of said tubular elements having two circumferentially extending slots spaced apart longitudinally of the tubular elements and a longitudinal slot joining the other slots, all of these slots forming two aligned circumferentially extending oppositely directed springs that bear upon the other tubular element which is formed to have abutting

and sliding engagement with the outer ends of said springs to prevent relative rotation of the tubular elements and to permit focal adjustment of the lamp.

2. A reflecting electric lamp including a reflector containing casing; a lamp; and two tubular elements, one within the other, one receiving the lamp and surrounded by the other that is connected with the casing, one of said tubular elements having a circumferentially extending slot and a longitudinal slot communicating with the other slot, these slots forming two aligned circumferentially extending oppositely directed springs that bear upon the other tubular element which is formed to have abutting and sliding engagement with the outer ends of said springs to prevent relative rotation of the tubular elements and to permit focal adjustment of the lamp.

3. A reflecting electric lamp including a reflector containing casing; a lamp; two tubular elements, one within and movable longitudinally of the other, one receiving the lamp and surrounded by the other that is connected with the casing, one of said tubular elements having a circumferentially extending slot and a longitudinal slot communicating with the other slot, these slots forming a circumferentially extending spring that bears upon the other tubular element normally to prevent relative longitudinal movement between said tubular elements; and means preventing material relative rotary movement of said tubular elements while permitting one of these elements to move longitudinally of the other.

In witness whereof I hereunto subscribe my name this 8th day of Nov., A. D. 1917.

HARRY A. DOUGLAS.
